UNITED STATES PATENT OFFICE.

JAMES ELLWOOD JONES, OF SWITCHBACK, WEST VIRGINIA.

COAL-HANDLING APPARATUS.

1,357,456.

Specification of Letters Patent.

Patented Nov. 2, 1920.

Application filed November 22, 1918. Serial No. 263,672.

To all whom it may concern:

Be it known that I, JAMES ELLWOOD JONES, a citizen of the United States, residing at Switchback, in the county of McDowell 5 and State of West Virginia, have invented certain new and useful Improvements in Coal-Handling Apparatus, of which the following is a specification.

This invention relates to coal handling apparatus designed particularly for use in handling of coal within the mine. Specifically, the invention contemplates a structure whereby the coal may be efficiently and quickly removed from the coal face and 10 deposited in mine cars from whence it is 15 transported to the tipple.

In the perfecting of this apparatus, one of the main objects resides in the provision of a structure whereby manual labor is reduced to a minimum and whereby actual shoveling by the miner is to all intents and purposes, eliminated. This invention may therefore be stated as residing in the combination with a coal handling machine capable of gathering the broken down coal 20 from the coal face and depositing it to the rear of the machine, of a scoop and mechanism associated therewith whereby this scoop may readily and easily attack the 25 deposited coal to convey it to a point of 30 discharge into the mine car. The object of associating a machine capable of gathering the coal from the coal face and redepositing it to the rear of the coal face is to 35 present conditions for the favorable operation of the scoop.

A further object of the invention resides in means associated with the apparatus already described whereby the point of attack of the scoop may be altered or varied 40 to suit conditions. In other words, the redeposited coal may be partially removed or all the coal may not be deposited at the same point and it is therefore an object of 45 this invention to provide a structure whereby the scoop may be rendered effective irrespective of the condition of the redeposited coal or of its location, all that is necessary being that sufficient room be provided for 50 the proper manipulation of the scoop itself.

The preferred embodiment of this invention is shown in the accompanying sheets of drawings wherein similar characters of reference designate corresponding parts and 55 wherein;

Figure 1 is a vertical section through a portion of a mine showing the apparatus in operation,

Fig. 2 is a top plan view of a portion of a mine also showing the apparatus in its 60 operative position,

Fig. 3 is a top plan view somewhat similar to that shown in Fig. 2 but on a considerably enlarged scale,

Fig. 4 is a side elevation of one form of 65 coal handling machine for gathering coal at the coal face and depositing it to the rear of the face,

Fig. 5 is a top plan view of the structure shown in Fig. 4, 70

Fig. 6 is a top plan view of the driving mechanism for the coal handling machine,

Fig. 7 is a cross section taken on line 7-7 of Fig. 6,

Fig. 8 is an enlarged detail view of the 75 brake mechanism associated with the differential drive of the rear axle of the structure shown in Fig. 6,

Fig. 9 is a cross section taken on line 9-9 of Fig. 6, and 80

Fig. 10 is a section taken on line 10 of Fig. 6.

In Figs. 1, 2 and 3 an entry has been 85 shown and is designated by the reference numeral 1 and tracks 2 are shown in position upon which the mine cars 3 are moved back and forth. Branching off of this entry at approximately right angles thereto are a plurality of rooms 4 which are illustrated as being partially worked, the coal being 90 removed to continue the driving of these rooms from the coal faces 5. It will be understood that this arrangement is what is known as room and pillar work but this particular layout of the mine is not essential 95 to the operation of the invention.

There is also shown a coal handling machine capable of gathering the blown down coal at its front end from the coal face and conveying it rearwardly to be deposited at 100 a point adjacent the rear end of the machine and sufficiently spaced from its operating parts to permit the successful and efficient operation of a scoop. This machine has been designated in its entirety 105 by the reference numeral 6 and the scoop is shown at 7. A haul line 8 and a drag line 9 are each connected to the front and rear end of the scoop respectively, these drag and haul lines being also associated 110

with suitable reeling mechanism carried by the conveying machine to facilitate the back and forth movement of the lines. At the entrance to the room there is shown a runway 10 having an inclined portion 11 leading from the level of the floor to a level exceeding that of the mine cars 3. At its upper end, this inclined portion is connected with a substantially horizontal portion 12 having an opening 13 therein located directly over the cars themselves. At its extreme rear end, this runway carries an idler or sheave 14 in any suitable or desirable manner over which the haul line 15 passes and then returns to the reeling mechanism by means of the line shown at 15. There is also shown an idler roller 16 located at the front end of the horizontal portion 12 of the runway which is of small enough diameter and also so located to permit the free passage of a scoop with its load of coal thereunder, it being understood that the diameter of the idler 14 is also sufficient so that the return strand 15 of the cable will not conflict with the loaded scoop.

From the description thus far given the operation is as follows:

After the coal has been blown down, the machine 6 is forced into the same and this broken coal is then conveyed rearwardly and deposited to the rear of the machine as illustrated in Fig. 1. During the time that this coal is being transferred, the reeling mechanism carried by the machine 6 is set in operation to move the scoop back and forth over the mine floor. Mechanism is also provided whereby the return movement of the scoop avoids the coal pile and then the movement toward the mine car may be directed so that the scoop will attack the coal pile. When this occurs, a quantity of the coal is confined by the scoop and slid forward by shortening of the haul line until it is forced up the inclined runway and close within reach of the opening 13. At this point, the coal is deposited in the car by passage through the opening and the scoop is then returned to a new starting position. The arrangement of rollers 14 and 16 is such that the drag line 15 does not interfere with the movement of the scoop in any manner.

The gathering machine itself comprises a conveyer pan 17 having an inclined forward portion 18 and horizontal forward portion 19. The rear end extends a considerable distance over the rear of the supporting truck designated generally by the reference numeral 20 so that coal may be deposited at this point without conflicting in any manner with the operation of the scoop. The conveyer itself consists of a chain passing over tail sprockets 21 and a head sprocket 22 which chain is confined within the guide-

ways 23. The chain itself is provided with a plurality of outwardly extending flights 24 designed to convey the material up one side or the other of the conveyer pan. It will be noted that this conveyer structure is provided with a comparatively wide nose and a narrow rear end and this is made so for the reason that the conveyer as a whole is mounted upon a truck capable of movement about the mine. In other words, the present type of machine is designed to be dumped directly into the coal pile and to in this manner attack the coal rather than by a sweeping movement back and forth across the mine room. However, the specific type of machine illustrated is not intended as a limitation as obviously, any type of machine capable of attacking the coal and conveying it rearwardly will suffice. Motor 6^a drives the conveyer chain through the gearing shown in Fig. 5. A motor 25 is mounted upon the conveyer truck frame and it is from this motor that the conveyer truck is driven and from which the machine derives its power to perform the various other functions to be described. The armature shaft of this motor carries a gear 25^a which meshes with a pinion 25^b mounted upon a shaft 26 which shaft drives the ordinary type of differential gearing carried by the rear axle 27 which gearing is confined within the casing 28. This rear axle also rigidly carries a pair of driving sprockets 29 over which the endless track 30 passes. At its forward end, this endless track passes over the sprocket 31 mounted upon the front axle 32, both axles being also suitably mounted within the truck frame work 20. Idlers 33 are provided to insure firm contact of the endless track or caterpillar tread with the mine floor. Thus, when the motor is turning in one direction, the machine as a whole is driven into the coal pile by means of a driving connection with the rear axle. This rear axle is also provided with a pair of brake drums 34 which coöperate with the brake bands 35, the ends of these brake bands are connected as is illustrated at 36 in Fig. 8 which also shows the operative connection of the rods 37 and 38 therewith. These rods 37 and 38 connect at their opposite ends to a lever 39 mounted upon the shafts 40 and 41 respectively. These latter shafts each carry operating levers 42 at their outer ends, the arrangement being such as indicated in Figs. 4 and 6. Thus, there has been employed the ordinary type of brake mechanism to operate in conjunction with the differential gearing to cause the machine to turn to various positions in attacking the broken down coal or to permit it to round corners when moving from one room to another. To obtain reverse movement it will be understood that the motor itself may be reversed.

The rear end of the bed plate 43 forming a portion of the truck 20 carries a pair of drums 44 which drums are comprised in the reeling mechanism already mentioned and 5 it is about these drums that the lines 9 and 15 are caused to be wound and unwound. In order to accomplish this from the motor 25, I have provided a shaft 26 with a clutch member 45 which is keyed thereto and slid- 10 able thereon and which is designed to engage the complementally formed clutch face on the sprocket 46 loosely mounted on this shaft. This sprocket 46 alines with a sprocket 47 on shaft 48 and drives the latter 15 by means of a chain 49 passing thereover. At its forward end, this shaft 48 carries a gear 50 designed to mesh with a complemental gear 51 mounted upon the shaft 52, the latter being suitably journaled on the under 20 side of the bed plate 43. At its forward end, this shaft 52 carries a bevel pinion 53 designed to mesh with bevel gear 54 carried upon the shaft 55 this latter also carries a spur pinion 56 meshing with the spur gear 25 57 carried by the shaft 58 upon which one of the drums 44 is mounted. The other drum 44 is mounted upon the shaft 59 and this shaft also carries the spur gear 60 which meshes with the spur pinion 61 car- 30 ried by the vertical shaft 62, this latter pinion 61 also meshing with the pinion 56 from which it derives its motion. From this it will be apparent that the drums 44 are re- 35 volved in opposite directions and that as the cable is paid out on the one, it is wound upon the other. These drums may be set in operation by operating the clutch member 45 which latter is operated by the hand lever 63 pivoted intermediate their ends as 40 shown at 64.

In order to govern the return movement of the scoop, it has been found necessary to return it in such manner that it will not ride over the coal pile which it has previously 45 attacked. To this end the main bed plate is provided with a shiftable arm 65 mounted to slide crosswise therein by means of the type of sliding connection shown at 66. This sliding connection also carries a rack 50 face 67 at its forward side to coöperate with a pinion 68 located on vertically disposed shaft 69 suitably journaled in connection with the bed plate as shown. On its opposite ends, this shiftable arm 65 is provided 55 with spools shown at 70 as rotatably mounted in an upright position and reference to Figs. 2 and 3 will indicate that the return line or drag line 9 passes over one of these spools before engaging the winding drum 44 shown at the bottom of Fig. 6. By shifting the arm 65 by rotation of the pinion 68 to any one of the dotted line positions shown in Figs. 2 and 3, the return movement of a scoop may be governed to avoid the rede- 60 posited coal. Immediately after the scoop 65 has returned to the rear of a coal pile, this arm may again be shifted to drag the scoop to a position in back of a coal pile so that its movement toward the mine car will cause it to attack the coal pile as will be readily apparent. When the arm 65 is shifted to the extreme right as shown in Fig. 3, the line 9 would ordinarily conflict with the drum 44 to which the line 15 is connected and to avoid this, I have suitably mounted a pair of 70 idler sheaves 71 and 72 to properly give the line 9 in connection with its drum 44.

In order to transmit power to the arm 65 to cause its shifting, the shaft 69 is provided with a beveled gear 73 and this beveled gear meshes with a complemental pinion 74 mounted upon the shaft 75 suitably journaled from the under side of the bed plate 43. At its opposite end, this shaft 75 carries a sprocket wheel 76 over which the chain 77 passes to engage the sprocket wheel 78 loosely mounted upon the main drive shaft 26. This latter sprocket is provided with a jaw clutch face designed to coöperate with the jaw clutch member 79 slidably keyed to the shaft 26 and operated by means of the levers 80 pivoted intermediate their ends as shown at 81. Thus, when the jaw clutch member is thrown into engagement with the sprocket 78, by operation of one 95 of the levers 80 the arm 65 is shifted in one direction and by reversing the motor this arm is shifted in the opposite direction. During the shifting of this arm, the entire machine is preferably standing still and in 100 order to permit this and at the same time permit the motor to operate, the shaft 26 is provided with a further jaw clutch member 26^a rigidly mounted thereto. This shaft 26 is split at this point and its continuation 26^a leading to the differential gears is provided with a complemental clutch member 82 slidably keyed thereto and operated by means of the levers 83 pivotally mounted intermediate their ends as shown at 84 whereby two jaw 110 clutch members may be thrown into engagement with each other to facilitate the forward movement of the machine as a whole. Likewise, should it be desired to turn a corner and shift the machine to one side or 115 the other the proper brake lever 42 is manipulated to tighten one of the brake bands 35 operating in connection with its drum 34 upon the rear axle. It will thus be apparent that the machine is capable of forward 120 movement to sump into the coal pile or it may be shifted to alter its point of attack by means of the brake drums and these same brake drums may be utilized in rounding a corner. Further, the same motor which effects the driving may be utilized to shift the arm 65 to any desired position to govern the 125 forward and return movements of the scoop.

It has often been found desirable to operate one drum to the exclusion of the other or to permit both to run idle such as when increasing the length of the cable or when making the various shifts ordinarily required during the mining operation. To this end, the drums 44 have been loosely mounted upon their shafts 58 and 59 and are caused to come into working engagement therewith by means of the clutch structure shown in Fig. 8. In this figure, the drums are shown as being formed with a conical concavity centrally arranged in which the cone member 85 operates. It is these cones, forming a portion of the drum structures which carry the gears 57 and 60. The shafts 58 and 59 are also provided with threads 86 at their upper ends upon which collars 87 complementally threaded are caused to operate. These collars are each provided with an annular channel to rotatably receive the drums proper 44 by means of a structure shown at 88. The extreme upper ends of each of the shafts 58 and 59 are rigidly connected to operating levers 89, these latter being in turn connected to operating rods 90 slidably mounted upon the structure as a whole. As shown in Fig. 6, the operating rod 90 is operatively connected with the lever 89 operating in conjunction with the shaft 58 while the other rod is shown as operating in connection with the lever mounted upon the shaft 59. Thus, when one of these rods is moving in one direction, the major portion of its drum 44 is elevated slightly and thereby released from frictional engagement with its corresponding cone portion 82 to run idle of its respective drive gear. In a similar manner, both drums may be caused to run idle or both may be positively driven as desired.

From the foregoing description, taken in connection with the accompanying sheets of drawings, it will be apparent that I have provided an apparatus which may be used to marked advantage in the removal of coal from the coal face. The conveyer structure is utilized to remove the coal from the coal face and deposit it in such position that it may be readily attacked by the scoop structure. The controller mechanism for the scoop is also so arranged that the scoop itself may be forced directly into the coal pile when traveling in one direction and may be made to avoid the coal pile when returning in the opposite direction. By this arrangement, the conveying mechanism may be maintained in operation independently of the operation of the scoop and therefore a sufficient quantity of coal may always be in position to be attacked by the scoop. By skilful operation, the redeposited coal pile may always be of such quantity that it will never be depleted during the interval required for the shifting of the conveying machine from

one position to another to properly clean out the blown down coal.

What I claim is:

1. In a mining apparatus, the combination with a coal handling machine comprising means for conveying the broken down coal from the coal face to a point in the rear of the coal face, of a scoop, drag and haul lines for said scoop, reeling mechanism for pulling said scoop into or out of a gallery, and means permitting manipulation of said lines so that said scoop returns to the rear of the redeposited coal by passing to one side thereof and then goes in the opposite direction to attack said redeposited coal. 80

2. In a mining apparatus, the combination with a coal handling machine comprising means for conveying the broken down coal from the coal face to a point in the rear of the coal face, of a scoop, drag and haul lines for said scoop, reeling mechanism for pulling said scoop into or out of a gallery, and means carried by said machine permitting manipulation of said lines so that said scoop returns to the rear of the redeposited coal by passing to one side thereof and then goes in the opposite direction to attack said redeposited coal. 90

3. In a mining apparatus, the combination with a coal handling machine comprising means for conveying the broken down coal from the coal face to a point in the rear of the coal face, of a scoop, drag and haul lines for said scoop, reeling mechanism for pulling said scoop into or out of a gallery, a shiftable arm carried by said machine, rope guide means carried by said arm and with which said drag line co-operates, and means for shifting said arm to variant positions with respect to said machine. 100 105

4. In a mining apparatus, the combination with a portable loading machine capable of collecting the coal at the coal face and depositing it on the floor in the rear of the machine, of a scoop, drag and haul lines for said scoop, reeling mechanism carried by said machine, and means permitting manipulation of said lines so that said scoop returns to the rear of the redeposited coal by passing to one side thereof and then goes in the opposite direction to attack said redeposited coal. 110 115

5. In a mining apparatus, a coal handling machine comprising a mobile truck, conveyer mechanism mounted on said truck to gather the coal at its front, convey it rearwardly, and deposit it to its rear, cable guiding means carried by said machine, means for shifting said guiding means to variant positions, in combination with a scoop, drag and haul lines connected to said scoop, and reeling mechanism for said lines. 120 125

In testimony whereof I affix my signature.

JAMES ELLWOOD JONES.
